UNITED STATES PATENT OFFICE

EDWIN E. DARRAGH, OF NEW YORK, N. Y.

DISPLAY CONTAINER

Application filed June 7, 1928. Serial No. 283,497.

This invention relates to improvements in that class of display boxes which serve not only as shipping boxes, but also as the counter containers for displaying the goods for sale.

5 It has been customary to utilize the front panel and display card of such boxes for suitable printed advertising matter, but unless the counter upon which it is displayed is above normal height, this advertising matter is not readily visible from above.

The main object of the present invention is to provide an improved display container which is readily set up in display position by a simple movement, which also produces a proper tilting of the display box front panel and display card, for display visibility from above.

15 The invention may further provide that the movement to display position produces a staggering or serration of the goods, or the boxes if the goods be separately boxed, securing improved visibility thereof and providing better access for their removal from above.

20 The invention may further provide that the movement to display position produces a staggering or serration of the goods, or the boxes if the goods be separately boxed, securing improved visibility thereof and providing better access for their removal from above.

25 Other objects and advantages will appear in the following description given in connection with preferred and modified embodiments of the invention which will now be described in detail in connection with the accompanying drawings forming a part of this specification and the features forming the invention will then be specifically pointed out in the claims.

30 In the drawings:

35 Figure 1 is an isometric view of a preferred form of a display box of a preferred form closed for shipping;

40 Figure 2 is an isometric view of the display box in display position;

45 Figures 3 and 4 are sections respectively on lines 3—3 of Figure 3 and 4—4 of Figure 2;

50 Figure 5 is a plan view of the display box blank;

55 Figure 6 is an isometric view similar to Figure 2 but with the packaged merchandise therein;

60 Figure 7 is an isometric view of a modified form of the display box partially opened;

65 Figure 8 is an isometric view of this box in display position;

70 Figure 9 is a section on line 9—9 of Figure 8;

75 Figure 10 is a plan view of this box blank;

80 Figure 11 is a plan view of a detail;

85 Figure 12 is an isometric view of another modification with a part of the display card displaced to show parts thereunder;

90 Figure 13 is an isometric view of this same box in display position with portions of the display card broken away;

95 Figures 14 and 15 are sections on, respectively, lines 14—14 of Figure 12 and 15—15 of Figure 13;

100 Figure 16 is a plan view of this box blank;

105 Figure 17 is a plan view of a detail;

110 Figure 18 is an isometric view of a further modification;

115 Figure 19 is an isometric view of this box in display position;

120 Figure 20 is a section on line 20—20 of Figure 19; and

125 Figure 21 is a plan view of the blank of this box.

130 Referring to the drawings and to the box of Figures 1 to 6 inclusive and in particular to Figure 5 thereof, reference character 10 designates the bottom of the box which carries at its opposite edges side panels 11, 12 and front and rear panels 13, 14, these panels being pivotally connected to the box bottom 10 by suitable scoring so that they may be bent upright to form the box body. The box front panel 13, which may be cut away as shown for display of the articles to be sold, carries on its opposite edges panels 15, 16, the panel 16 being extended to provide a panel 17 and a securing tab 18 separated by suitable scoring, so that they, together with front panel 13, form a band enclosing the box body formed by bending the panels 11, 12, 13 and 14, upright about the bottom panel 10. The band may be secured about the box body in any suitable manner as by gluing tab 18 to the inside of panel 15.

135 The bottom edges of the panels 15, 16 are cut off as shown at 15', 16' and the rear band panel 17 is formed of the same width as the smaller dimensions of these panels, so that

when the band is connected together about the box body, the rear portion of the band is narrower than the front panel 13, thus allowing the band to be moved downwardly 5 with the line of scoring connecting front panel 13 with the box bottom 10 as its pivotal point or hinge.

In the preferred form of box shown by these figures, those edges of the box body 10 panels 11 and 12 which abut the front panel 13 are correspondingly cut off at 11', 12' to allow the panels 13, 14 to move backward or tilt back about their lines of scoring connecting with box bottom 10, which movement 15 causes the articles within the box to assume the stepped or serrated position shown in Figure 6.

Band panel 17 may be provided with an extension as shown, which forms the box 20 cover and is suitably scored to provide cover portion 19, adapted to cover the top of the box, and closure sections 20 and 21 for closing the open front panel 13 and for a purpose to be hereinafter explained.

25 The box body rear panel 14 carries a display card 22, which is preferably of the type shown in my application Serial No. 178,170, filed March 15, 1927, comprising a lower portion within the box which is slightly wider than the box body and is divided into a plurality of sections, *a*, *b*, *c*, the central section *b* being secured to the rear panel 14 by glue or in any other suitable manner, the other sections *a* and *c* being compressed edgewise 30 by the sides of the box to retain the display portion of the card in display position.

The operation of the box is as follows: With the box resting upon a table as shown in Figure 1, the cover formed by cover portion 40 19, and sections 20, 21 are raised and swung about the upper rear edge of the box. The display card 22 is then swung up into position and pressure is applied to the opposite rear side edges of the band, causing the rear portion of the band to move downwardly about the box body and rest upon the table. This movement of the box band about and relative to the box body causes the front panel 13 and the display card 22 to tilt back and 45 assume such an angle thereto that they are readily visible from above. The tilting back of this box also causes a corresponding movement of the articles therein, as shown in Figure 6, producing a stepping or serration 50 thereof for display and ease in removal.

In oblong boxes designed to stand upon one of their smaller panels, it is desirable to provide a support for the rear of the box. For this purpose the box cover may be rotated about its scored connection to rear band 60 panel 17 and the section 21 folded about the opposite side of the panel 17, with the section 20 horizontal, the sections 19, 20, 21 thus forming a firm rear support for the box, as 65 shown in Figure 4.

The modification shown in Figures 7 to 11 inclusive, comprises a box body formed by bottom panel 110, side panels 111, 112 and front and rear panels 113, 114 enclosed by a band formed by band side panels 115, 116, 70 carried by front panel 113, the rear band panel 117 secured about the box body by gluing tab 118 to the inside of band side panel 115, the band being hingedly secured to the box body by the line of scoring between the front panel 113 and the box bottom 110. The box is provided with a display card 122 which is separate from the box and secured thereto by passing its lower end between the band rear panel 117 and the box body rear panel 114 and gluing the same to the panel 117. The band side panels 115, 116 may carry respectively tabs 123, 124, which are so scored as to be bent down over the box contents during shipment. When the box is moved 80 to display position, however, the corners of the box body rear panel 114 engage and raise the tabs 123, 124. The corners 114' are preferably cut off slightly, as shown, so that tabs 123, 124 are not moved to perpendicular 90 position but overlie the edges of the display card so as to hold it erect.

A feature of this box resides in that a platform or display stand is provided for displaying in prominent position one or more 95 of the articles on sale. This platform may be readily secured in various ways, but I have shown it, by way of illustration, as formed as a part of the display card 122. For this purpose the display card 122 is so cut as to 100 form a platform panel 125 and a prop or supporting tab 126 hingedly connected by suitable scoring which coincides with the line of display card scoring usually provided to permit the display card 122 to be bent down 105 within the box during shipment, the platform panel 125 being connected to the display card 122 by scoring 125'. When the display card is secured to the box, the tab 126 overlies the interior of the box body rear panel 114 110 and is of such length that its end rests upon the box bottom 110. If desired, the tab 126 may be provided with a tongue 127 adapted to engage a suitable slit 128 formed in the line of scoring connecting box bottom 110 115 and the body rear panel 114 to secure the tab 126 in position. When the box is tilted back to display position, the downward movement of the box band carries with it the display card 122 causing the tab 126 to raise the platform 125 at right angles to the display card 122 for the support of one or more sample articles. Furthermore, if desired, an offset display panel 129 may also be cut from the display card above the platform 125 and preferably forms an extension thereof, so as to be 120 operated by the tab 126, the upper end of panel 129 being connected to the display card 122 by straps 130 hingedly connected thereto by suitable lines of scoring. Thus the tilt-

ing back of the box not only produces a platform but also moves the offset display panel 129 outwardly from the display card 122 for emphasis thereof.

5 The modification shown in Figures 12 to 17 inclusive is similar to the preferred construction described in connection with Figures 1 to 6 inclusive in that the box blank provides a body portion formed by bottom 210, side panels 211, 212 and front and rear panels respectively, 213 and 214 and a band enclosing this box body provided by panels 215, 216 and 217, secured about the box body by gluing tab 218 to the inner side of the 15 panel 215. In this construction, however, I provide an automatic support for the rear of the box, said support opening automatically during the tilt-back movement of the box. For this purpose I preferably cut a 20 portion or member from the rear panel 214 of the box body which is suitably scored to provide panels 231, 232, and a tab 233. During the assembling of the box this portion or member is passed outside the rear panel 217 25 of the box band and tab 233 is passed through a suitable slot 234 provided therein, the location of the slot 234 being such that when the box is in shipping position, the support lies flat against the panels 214 and 217. When 30 the box is moved to display position, the downward movement of the band causes support panel 231 to lie flat on the counter and hold panel 232 at a proper angle to the rear of the box for proper support thereof.

35 A further feature of this box resides in the fact that tabs 235, 236 are cut from the opposite upper corners of the box body rear panel 214 and are suitably scored so that when the box is tilted back into display position, the tabs 235 and 236 pass above the upper edge of the rear band panel 217 and due to their scoring bend outward or are bent outward by the operator so as to lock the box in display position.

40 45 The display card 222 of this modification is held erect in a novel manner by cutting therefrom a tongue portion 237, which is glued to the rear band panel 217, the remainder of the lower end of the display card 222 then passing over the box body rear panel 214 into the interior of the box, so that when the box is tilted back into display position, the box body rear panel 214 passes up between the tab 237 and the remainder of the 50 55 display card 222 to a point well above its line of scoring and positively holds the display card in display position.

In the modification shown in Figures 18 to 20 inclusive, a board feature of the invention is illustrated in its simplest form, in which the band moves relatively to the box body to secure proper angling of the front panel and display card, but is not accompanied by any movement of the box body 60 parts or of the goods therein. As in the

prior constructions, the box body is formed by bottom panel 310, side panels 311, 312 and front and rear panels respectively, 313, 314, but differs in that panel 313 is provided with extension 313' separated therefrom by suitable scoring to provide a band front panel which carries side band panels 315, 316, rear band panel 317 and securing tab 318. In this instance the panels 315 and 316 are acute angled parallelograms and the rear band panel 317 is of materially less depth than these panels. In setting up the box, the panels 311, 312, 313 and 314 are bent up at right angles to the box bottom 310 and panel 313' is then bent downwardly about the scoring line separating it from panel 313 and panels 315, 316 and 317 are passed around the box thus formed and secured together by gluing tab 318 to the interior of the band side panel 315 as heretofore. As readily perceived from the drawings, the box band pivots about the line of scoring between panels 313' and 313 when the band is pushed downwardly for movement into display position. In this construction, as shown, the display card 338 preferably forms a continuation of the box body rear panel 314 and is preferably separated therefrom by scoring applied in such manner that the tendency of the display card 338 upon movement of the box into display position is to follow the movement of the box band rear panel 317 and lie thereagainst.

It will be understood that the invention is not to be limited to the specific constructions shown as embodiments of the invention, but that many modifications may be made while retaining the invention defined by the claims.

I claim:

1. A display box having a band encircling the box and hinged to swing vertically on one wall of the box, and means permitting swinging movement of the band relative to the box.

2. A display box having a band encircling the box and hinged at the front of the box to swing vertically, said band lying above the bottom of the box in its erect position whereby the depression of the band tilts the band backward for display.

3. A display box having a band encircling the box and hinged at the front of the box to swing vertically, said box and band being made from a single blank, said band lying above the bottom of the box in its erect position whereby the depression of the band tilts the band backward for display.

4. A display box having a band encircling the box, one panel of the band forming one front wall of the box, said band being mounted to swing vertically with said box wall and the lower edge of the rear band panel lying above the bottom of the box in its erect position whereby the swinging of the band tilts the band and box.

5. A display box having a band encircling

- the box, one panel of the band forming the front wall of the box, said band being mounted to swing vertically with the box front and said band lying above the bottom of the box in its erect position, whereby the depression of the band tilts the band and box backward for display.
6. A display box having a band encircling the box, one panel of the band forming the front wall of the box, said band and box being made from a single blank, said band being mounted to swing vertically with said box front wall and said band lying above the bottom of the box in its erect position, whereby the depression of the band tilts the band and box backward for display.
7. A display box having a band encircling the box and hinged to swing vertically on one wall of the box, whereby the swinging of the band tilts the band, and a support for the rear wall of the box carried by the band and folding on the box for packing.
8. A display box having a band encircling the box, one panel of the band forming the front wall of the box, said band being mounted to swing vertically with the said box front wall and said band lying above the bottom of the box in its erect position, whereby the depression of the band tilts the band and box backward for display, and a cover for the top and front of the box carried by the band and folding to form a support for the rear wall of the box.
9. A display box having a band encircling the box, one panel of the band forming the front wall of the box, said band being mounted to swing vertically with said box front wall and said band lying above the bottom of the box in its erect position, whereby the depression of the band tilts the band and box backward for display, and a cover for the top and front of the box formed of three panels whereby the cover may be swung over the rear side of the box and the end cover panel inserted between the band and box to hold the cover in triangular form to form a support for the rear wall of the box.
10. A display box having a band encircling the box, one panel of the band forming the front wall of the box, said band being mounted to swing vertically with the box front and said band lying above the bottom of the box in its erect position, whereby the depression of the band tilts the band and box backward for display, the rear panel of the box carrying a folding support connected to the rear panel of the band to lie along the panels in the erect position of the box and to be moved from the panels by the tilting of the box to form a support for the rear wall of the box.
11. A box blank having bottom, side, front and rear panels, and band panels on the sides of one of the vertical box panels forming with said box panel a band extending around the side panels of the box and hinged to swing vertically thereon, the adjacent band panels and box side panels being cut away to allow the box to tilt when the band is swung.
12. A box blank having bottom, side, front and rear panels, and band panels on the sides of the front panel forming with the front panel a band extending around the side and rear panels of the box and hinged to swing vertically thereon, the adjacent band panels and box panels being cut away to allow the box to tilt when the band is swung.
13. A display box having its front and rear walls free to pivot on the box bottom from erect to tilted position.
14. A display box having front, rear and side panels pivoted on the box bottom and free to be tilted backward for display.
15. A display box having a band encircling the box and hinged to swing vertically on one wall of the box, the rear panel of said band being displaced upward relatively to the front panel of said band, whereby swinging of the band tilts the band.
16. A display box having a band encircling the box and hinged to swing vertically on one wall of the box, the lower edge of the rear band panel lying above the bottom of the box in its erect position, whereby the depression of the band tilts the band.
17. A display box having a band encircling the box and hinged to swing vertically on one wall of the box, the rear panel of said band being smaller vertically than the front band panel, whereby swinging of the band tilts the box.
18. A display box having a band encircling the box and hinged to swing vertically on one wall of the box, the side and rear panels of said band being adapted to permit swinging movement of the band about the box to tilt the band.
19. A box blank having bottom, side, front and rear panels, and band panels arranged to form a band extending around the side panels of the box and hinged to swing vertically on the box, the lower edge of the rear band panel lying above the bottom of the box in its erect position.
20. A box blank having bottom, side, front, and rear panels, and band panels arranged to form a band extending around the side panels of the box and hinged to swing vertically on the box, the lower edges of the band side and rear panels lying above the bottom of the box in its erect position.
- In testimony whereof, I have hereunto set my hand.
- EDWIN E. DARRAGH.
